United States Patent Office

Des. 178,957
Patented Oct. 16, 1956

178,957

BOX

Benjamin Greenstein, Bronx, and Carl Molk,
New York, N. Y.

Application September 19, 1955, Serial No. 37,987

Term of patent 7 years

(Cl. D58—11)

FIG. 1.

FIG. 2.

FIG. 3.

Fig. 1 is a front perspective view of a box, showing our new design;

Fig. 2 is a side elevational view thereof; and

Fig. 3 is a cross-sectional view thereof, taken on the line 3—3 of Fig. 1.

The rear view and the opposite side view of the box are the same as the front view and side elevational view, respectively, as shown.

We claim:

The ornamental design for a box, as shown and described.
